PROFILOMETER

Adolph Grauer, New York, N. Y.

Application May 1, 1942, Serial No. 441,396

10 Claims. (Cl. 33—23)

It is among the objects of the present invention to provide a profilometer which will readily give an accurate trace with greatly and proportionately foreshortened horizontal or abscissa dimension of the profile of a road so as to show clearly the variations thereof from specifications.

Another object is to provide a knockdown device of the above type made almost entirely of bar stock which shall be inexpensive in construction and easy to transport, easy to set up for use and easy to operate.

According to the invention the profilometer comprises a horizontal open framework presenting a track, a vertical follower unit to ride along said track, and carrying a marking device, a chart mounting carriage also riding along said track and interlocked with said follower unit to advance the latter with respect to the former at a greatly reduced proportional rate in the travel of the chart supporting carriage along the track.

In the accompanying drawings in which is shown one of various possible embodiments of the several features of the invention,

Fig. 1 is a view in front elevation showing the apparatus as used.

Fig. 2 is a view of the follower and marking portion of the assembly of Fig. 1 and on a much larger scale.

Fig. 3 is a vertical sectional view taken on line 3—3 of Fig. 2,

Fig. 4 is a transverse sectional view taken along line 4—4 of Fig. 2,

Figs. 5 and 6 are transverse sectional detail views taken respectively on lines 5—5 and 6—6 of Fig. 2,

Fig. 7 is a view on a larger scale showing the mode of assembly of the supporting framework,

Fig. 8 is a detail sectional view taken on line 8—8 of Fig. 7,

Fig. 9 is a transverse sectional detail view on line 9—9 of Fig. 1, and

Fig. 10 is a transverse sectional detail view on line 10—10 of Fig. 9.

Referring now to the drawings, the invention comprises a main or support framework 11 which may be of any suitable construction, desirably a knockdown construction, and which has support legs or feet 12 at the ends thereof. This frame desirably is of an open truss construction as shown, made up of a plurality of truss sections 11^a with adjacent struts 12 clamped together by bolts 13 and coacting nuts 14 in manner readily understood.

The framework presents a horizontal longitudinal upper web 15 and a corresponding lower web

16 which serve as tracks. Carried by said webs is a sheath 17 extending vertically and serving as a mount for the follower bar 18 by which the profile is to be traced. The sheath comprises a channel bar 19 with inturned longitudinal flanges 20. Small rollers 21 extend across the lateral pockets of the sheath, the axles 22 of said rollers traversing said pockets and being affixed in the back and respective flanges 20 of the sheath. The rollers 21 engage the edges of the follower bar 18 which is thus slidably positional in said sheath.

Welded or otherwise secured to the back of the sheath is a carrier plate 23 the lower end of which has an inturned ledge 24 with an upturned flange 25 which supports small rollers 26 riding along and under the lower track 16 of the framework. Similar transverse rollers 27 ride upon the upper web or track 15 of the framework. The axles 28 of said rollers are lodged respectively in plate 23 and the flange 29 thereof. The sheath accordingly is guided by the four rollers 26 and 27 for ready movement along the framework and is retained thereby against tilting from its position at right angles to the length of framework 11.

The follower bar 18 is desirably hollow so as to mount at the lower end thereof a follower wheel 30 on an axle 31 transversely therethrough. A sleeve 32 carrying a marking implement 33 spring pressed as at 34 encircles the upper part 30 of the follower bar 18, said sleeve being adjustably affixed thereto by means of the set screw 35.

Coacting with the marking element is the chart mounting carriage which comprises a rectangular frame 36 affording backing for a removable sheet of cross-section or other charting paper. This frame is mounted vertically upon the main framework and for that purpose is provided with end brackets 37 having grooved rollers 38 on vertical axes, said rollers accommodating the lateral edges of the track web 15 so that the chart frame may readily travel along the framework with but little friction.

A speed reducing transmission is interposed between the follower sheath 17 and the chart mounting frame 36 so that the former will advance with respect thereto at greatly reduced proportional rate in the travel of the chart mounting frame along the track. Desirably the reducing mechanism comprises a rack and pinion transmission. This includes a long rack 39 extending substantially the entire length of the framework under and adjacent the upper track 15 thereof. The chart mounting frame has rigidly mounted upon a narrow web 40 on the lower edge thereof a shorter rack 41. The transmitting

gearing between racks 39 and 41 is retained by a flat transmission box 42 formed desirably as a unitary part of the follower sheath structure 17. The gear box has a gear 43 exposed at the under face thereof and meshing with rack 39, and a pinion 44 exposed at the upper face thereof and meshing with rack 41. The drive between gear 43 and pinion 44 involves a pair of gears 45 and 46 within the flat gear case 42, gear 45 being rigid with and mounted on the same pin 47 as gear 43 and the gear 46 being rigid with and mounted on the same pin 48 as pinion 44.

The chart mounting frame or, if desired, the supporting framework, is provided with a spirit level 49 to permit adjustment of the parts so that the track 15 will extend in substantially horizontal position regardless of the inclination of the road. To permit such adjustment the supporting legs at the ends of the main or support framework are adjustable in height. To this end these legs may be of T-bar structure as at 50 extending in corresponding slots 51 in foot-pieces 12 and clamped in position by set screws 52.

The operation will be clear from the foregoing description, but will nevertheless be briefly summarized. The portable profilometer in knock-down condition, delivered by truck to the road section to be measured, is readily put together by assembling the truss frame sections 11^a by means of the bolts 13 and nuts 14, as shown in Figs. 7 and 8. The device being positioned transversely of the road from the crown to the gutter or curb thereof the feet 12 are adjusted in height until the spirit level 49 indicates the horizontal relation of the tracks. In any setting the follower bar 18 will automatically slide downward along the rollers 21 so that the follower wheel 30 will touch the ground. The marking element 33 is brought in contact with the chart on frame 38. It is merely necessary now to push the chart mounting carriage 36 longitudinally along the track 15 from one end to the other thereof. In this operation the follower wheel 30 will enter any depression and follow any elevation in the road and will cause the pencil or marking implement 33, which is rigid therewith, correspondingly to trace the variations in height and depth in the road. The horizontal length of the trace will, however, be but a small fraction of the length of the road section being traced. This is due to the fact that in the advance of the chart mounting carriage 36 the rack 41 will rotate the pinion 44 and the latter through gear 46 will rotate gear 45 and with it gear 43 and since the latter meshes with the fixed rack 39 advance of sheath 17 with the follower bar 18 and marking element 33 will occur relative to the chart carriage 36 at a rate determined by and proportioned to the gear reduction. Desirably, the rate is such that say for a 30-foot length of framework traversed by the chart carrying frame, the marking element will make a line but three feet long on the chart.

The sleeve 32 that carries the marking implement or pencil 33 is arranged to be adjustable in position lengthwise of the follower bar so that successive sections of the road may be traced in generally parallel relation upon one and the same chart.

It will be understood that the invention is not limited to tracing transverse profiles of the road but could also be used for tracing such profiles longitudinally of the road.

As many changes could be made in the above

construction and many apparently widely different embodiments of this invention could be made without departing from the scope of the claims, it is intended that all matter contained in the above description or shown in the accompanying drawings shall be interpreted as illustrative and not in a limiting sense.

Having thus described my invention, what I claim as new and desire to secure by Letters Patent of the United States is:

1. A profilometer comprising a support frame having a track along the length thereof, a chart mounting carriage adapted to ride along said track, an upstanding follower and marking structure having a roller support upon said frame, said chart mounting carriage and said follower structure having a speed reducing transmission therebetween to cause one of said elements to move horizontally relative to the other at a speed but a predetermined fraction of that at which said carriage is moved along the track.

2. A profilometer comprising an elongated support frame presenting a track, an upstanding chart mounting carriage supported upon said track to ride therewith, an upstanding follower member having means at one end engaging the road and carrying a marking implement correlated with the chart, track means for guiding the vertical movement of said follower member with respect to said carriage and a speed reducing transmission between said chart carriage and said follower member to cause the latter to move horizontally relative to the chart carriage in the propulsion of the latter along the frame.

3. A profilometer comprising an elongated support frame having feet at the ends thereof, said frame having a track therealong, a chart mounting carriage having rollers riding along said track, an upstanding follower unit mounted to ride along said support frame, having a road follower at its lower end and a marking element adjustably carried thereon for coaction with the chart, and a rack along said carriage, a rack along said elongated frame and intervening gear reduction mechanism carried by said follower unit and determining the horizontal movement of the latter relative to the carriage in the movement of said carriage along the frame.

4. A profilometer comprising an elongated support frame having a track along the upper part thereof, a chart mounting carriage, support rollers therefor riding along said track, a coacting upstanding follower unit having roller supports riding along said support frame, and having a follower at the lower end thereof and a marking element carried thereby coacting with the chart, a rack carried by and extending along said support frame, a shorter rack carried by the chart mounting carriage and a speed reducing gear transmission connecting said racks and mounted upon said follower unit to cause the latter to advance at a greatly reduced proportional rate with respect to said chart carriage in the horizontal movement of the latter along the support frame.

5. A profilometer comprising an open support frame having feet at its ends and presenting a track along the top thereof and a second track along the bottom thereof, a combined follower and marking unit comprising an upright member having a roller at its lower end to contact the road and having a marking element carried at an upper part thereof, rollers on said unit respectively riding over the top and under the bottom track of said support frame, a rack ex-

tending substantially the length of said support frame, a reducing gear transmission carried by said unit and including a gear meshing with said rack, a chart mounting carriage having a roller support upon the upper track and coacting with the marking element of said unit, a shorter rack along the lower part of said chart mounting carriage and a pinion driven from said first rack and meshing with said shorter rack.

6. A profilometer comprising a knockdown open framework having support feet and presenting a track longitudinally thereof, means for leveling said track regardless of the inclination of the road, a follower unit having means coacting with said frame to maintain said unit substantially at right angles to said framework, and in coaction with said track for riding therealong, said follower unit having a marking implement thereon, a chart mounting carriage having roller support on said track, a rack along the length of said framework near the track thereof, a shorter rack carried by the lower part of said chart mounting carriage and a gear transmission carried by said follower unit, and constituting a reduction drive between the rack on the support frame and the shorter rack on the chart mounting carriage.

7. A profilometer comprising an open knock-down truss framework, presenting a horizontal web along the top thereof defining a track, a follower unit having rollers transversely of said web and riding thereon, and companion rollers riding under and along the lower part of said frame and maintained thereby in strictly vertical position, a chart mounting carriage having support rollers straddling and riding along the lateral edges of said web track and coacting with the marking element of said follower unit, a larger rack affixed to and extending longitudinally of said framework adjacent said track, a second shorter rack extending along the lower part of said chart mounting carriage, and a series of spur gears mounted upon said follower

unit and constituting a reduction transmission between said racks to predetermine a relative horizontal movement between the chart mounting carriage and the follower unit in the movement of the former.

5 8. The combination recited in claim 7 in which the gear transmission comprises a horizontal flat gear-case mounted upon said follower unit, having a gear exposed therebelow and meshing with said longer rack, a gear rigid therewith within said case, a corresponding larger gear within said case meshing with the latter, and a pinion rigid with said gear and exposed above said case and meshing with the shorter rack.

10 15 9. A profilometer comprising a horizontal support frame presenting an upper and a lower horizontal track, a vertical sheath having rollers straddling said support frame, a follower bar lodged in said sheath, said sheath having rollers engaging said bar to permit the lower end thereof to contact the road, a rearward extending plate at the upper end of said sheath, reduction gearing carried by said plate, a rack on said support frame meshing with said gearing, a chart mounting carriage having rollers riding on the track of said support frame, a horizontal rack carried by the lower part of said chart mounting carriage, said gear reduction including a pinion meshing with said latter rack.

20 25 30 35 40 10. A profilometer comprising a horizontal, open support frame having end legs mounting the same, means for leveling said frame, a vertical sheath having a roller support on said frame, a follower bar having a roller support in said sheath, a chart mounting carriage having a roller mount upon said support frame, a fixed rack upon and along the length of said support frame, a shorter rack mounted on said chart mounting carriage and a reducing gear transmission between said racks, said transmission having mounting means carried by said sheath.

ADOLPH GRAUER.
